UNITED STATES PATENT OFFICE.

WILL G. HOAGLAND, OF INDEPENDENCE, KANSAS.

BOILER.

Application filed August 11, 1923. Serial No. 656,791.

This invention relates to water boilers and has for its object the provision of a sectional water tube boiler designed for general use and so constructed that there is a continuous circulation which will prevent the formation of scale on the tubes, the arrangement being furthermore such that there is never any direct heat applied to the mud ring, hence avoiding hardening, burning or sticking of any sediment therein.

Another object is the provision of a device of this character which will be simple and inexpensive in manufacture, highly efficient in use, durable in service and a general improvement in the art.

With the above and other objects and advantages in view the invention consists in the details of construction to be hereinafter more fully described and claimed and illustrated in the accompanying drawings, in which:

Figure 1 is a side elevation of the device,
Figure 2 is a front elevation,
Figure 3 is a top plan view,

Figure 4 is a vertical section taken from front to back, on the line 4—4 of Figure 1.

Referring more particularly to the drawings the numeral 10 designates the steam dome or header into which lead horizontal pipes 11 connected with the upper ends of two spaced series of upright sections 12 which have their lower ends connected with a mud ring 13. Between the mud ring and the sections 12 are connections 14 and interposed in the horizontal tubes or pipes 11 are similar connections 15 which permit detachment of any portions of the device when such is necessary. Leading from the mud ring 13 is a circulating pipe 16 which also leads into the bottom of the dome 10 at one end thereof and interposed in this circulating pipe is a connection 17 which will permit detachment of the parts.

The water inlet, not shown, is connected with the circulating pipe 16 at the point 18, while the steam outlet from the dome is shown at 19. At the bottom of the device is a blow off lug 20.

Extending across the device are two blanks 50 of tubes 21 and 22 which lead from each pair of upright pipes or from the upper sections 12 at one side to the lower sections at the opposite side in crossed relation as

shown. The tubes in one bank or series are bent or offset as shown to avoid the other. Within the members 12 or between the connections of the banks 21 and 22 therewith are partitions 22^a which will prevent free passage of water directly through the members 12 into the members 11, the water 60 being consequently compelled to take a circuitous course.

In the operation water is admitted at the point 18 and goes down to the mud ring 13. The water rises from the ring through the 65 connections 14 into the sections 12 where it is exposed to heat by any desired means or from any proper source. The heated water rises through the banks of tubes 21 and 22 to the upper sections and enters the dome 10, 70 the steam being taken therefrom at the connection 19, and the water returning through the circulating pipe 16 to the mud ring. This operation is continuous and it is to be noted that there is a continuous circulation 75 which will prevent the formation of scale. Owing to the fact that the mud ring is not exposed to direct heat there will be no burning, baking or hardening of the sediment which may accumulate therein and the device will therefore not clog but should give 80 long and satisfactory service.

While I have shown and described the preferred embodiment of the invention it is of course to be understood that I reserve the 85 right to make such changes in the form, construction and arrangement of parts as will not depart from the spirit of the invention or the scope of the subjoined claim.

Having thus described my invention I 90 claim:

In a boiler of the character described, a mud ring, a longitudinally extending dome located above the mud ring at a point above the center thereof and of considerably less 95 width than the mud ring, a plurality of upright pipes connected with the sides of the mud ring and terminating in horizontal inward extensions leading into the opposite sides of the dome, a steam outlet at the center of the top of the dome, a circulating pipe connecting the mud ring and the dome at one end of the latter and equipped with a water inlet, and a plurality of series of tubes arranged in interfitting relation, there 100 being two banks or series of tubes for each

pair of upright pipes, one bank or series of therewith, and the tubes of one bank or tubes of each pair connecting at one end series being offset to be out of alinement with the lower portion of one upright pipe with those of the other series to avoid the same.

5 of the opposite upright pipe, said upright pipes being provided with partitions between the connections of the banks of tubes

In testimony whereof I affix my signature.

WILL G. HOAGLAND.
